UNITED STATES PATENT OFFICE.

JAMES A. SILSSEE, OF ELMIRA, NEW YORK.

UNIVERSAL-MOTION OPERATING DEVICE.

1,285,814.

Specification of Letters Patent Patented Nov. 26, 1918.

Application filed February 2, 1918. Serial No. 215,151.

To all whom it may concern:

Be it known that I, JAMES A. SILSSEE, a citizen of the United States of America, residing at Elmira, in the county of Chemung 5 and State of New York, have invented certain new and useful Improvements in Universal-Motion Operating Devices, of which the following is a specification.

The primary object of the invention is the provision of a ready means for controlling at a distance such devices as spot and search-lights and the like, where movements in different directions are required to be accurately controlled, my structure being simple 15 in arrangement and eliminating any cumbersome or complicated mechanism.

A further object of the invention is the provision of mechanism whereby oscillatory and rotary movement may be imparted to 20 any article desired, such movements being performed either separately in the desired direction or simultaneously in either of the oscillating and either of the rotary directions.

25 The general objects of the invention being those herein noted, one adaptation of the device is presented for purposes of illustration and consists of a headlight for an automobile adjustably operated by the device 30 from a point adjacent the driver's seat of the vehicle.

With these general objects in view and others that will appear as the nature of the invention is better understood, the same consists in the novel combination and arrangement of parts hereinafter more fully described illustrated in the accompanying drawings and pointed out in the appended claims.

40 In the drawings forming a part of this application and in which like designating characters refer to corresponding parts throughout the several views,

Figure 1 is a side view of the forward 45 portion of an automobile partly broken away with the device operatively arranged thereon.

Fig. 2 is a top plan view of the mounting base employed with the device for supporting the member to be moved, such as a searchlight.

Fig. 3 is a side elevation of a searchlight arranged upon the base.

Fig. 4 is a vertical longitudinal sectional 55 view taken upon line IV-IV of Fig. 2.

Fig. 5 is a vertical transverse sectional view taken upon line V-V of Fig. 3.

Fig. 6 is a front elevation of the operating valve.

Fig. 7 is a top plan view thereof.

Fig. 8 is a top plan view of the valve casing.

Figs. 9 and 10 are vertical sectional views taken through the casing upon planes perpendicular to each other.

Figs. 11 and 12 are elevational views of different sides of the valve plug or turn member.

Fig. 13 is a top plan view thereof.

Fig. 14 is a central longitudinal sectional 70 view of the same.

Figs. 15 and 16 are elevational views of different sides of the auxiliary plug employed with the main plug illustrated in Figs. 11, 12, 13 and 14 and

75 Figs. 17 and 18 are elevational views of the opposite ends of the said auxiliary plug.

The embodiment of the device now set forth is illustrated in connection with an automobile 10 having a body 11, driver's 80 seat 12, steering wheel 13, wind shield 14, and dash or instrument board 15, the invention broadly consisting of an operating member 16 mounted upon the dash board adapted for controlling the movements of searchlight 85 mechanism 17 positioned upon a bracket 18 forwardly of the radiator 19 of the vehicle.

A cruciform base 19 is arranged for adjustably mounting the searchlight proper or lamp 20 thereon, a pivot screw 21 being 90 fixedly threaded in the base 19 adjacent one of the side arms 22 thereof while a yoke 23 is journaled upon said screw by means of its boss 24 and the lamp 20 is swingingly mounted in the yoke by trunnions 25. A cylinder 26 is fixedly secured upon a suitable post 27 laterally projecting from the yoke 23 and is arranged with a piston 28 adapted to reciprocate therein.

A rod 29 is provided for the piston 28 slidably passing through a stuffing box 30 in the upper end of the cylinder 26, the said rod being operatively connected by means of a crank or link 31 with an arm 32 of the adjacent trunnion 25 of the lamp 20. It will be 100 understood that by creating a partial vacuum in the cylinder 26 beneath the piston 28 by exhausting the air through a pipe or connection 33 in the manner hereinafter set forth, the said piston will be lowered corre- 110

spondingly tilting the lamp 20 downwardly or forwardly. A similar pipe 34 enters the cylinder 26 adjacent its upper end adapted for exhausting the air above the piston 28, 5 which elevates the said piston and tilts the lamp 20 upwardly.

The base 19 is provided with a longitudinally arranged chamber 35 having a piston 36 slidably arranged therein with a rod 37 passing through a stuffing box 38 at one end of the base 19 with its outer ends secured to a depending finger 39 of a toothed rack 40 slidably mounted upon the top 41 of the base 19. The said rack 40 has a depending 15 rib 42 slidably arranged within the longitudinal groove 43 substantially centrally positioned in said base top 41 while a substantially Z-shaped clip 44 is secured to the base 19 and overlies the rack 40 for retaining the 20 latter within the groove 43.

A pinion 45 is keyed to the boss 24 in constant mesh with the teeth of the rack 40 and it will be evident that a movement of the piston 36 will impart rotary movement 25 to the yoke 23 and lamp 20. A pipe 46 communicates with the piston chamber 35 adjacent the forward end of the base 19, that is the end of the base which is forwardly of the lamp 20, while a similar pipe 47 communicates with the chamber 35 at a point 30 adjacent the rear end of the base 19. By exhausting the air forwardly of the piston 36 through the pipe 46, the said piston as well as the rack 40 will be moved forwardly 35 thereby turning the lamp 20 toward the right, while an exhausting of the air through the pipe 47 effects a rearward movement of the rack 40 turning the said lamp toward the left hand side of the base 19 and vehicle 40 10. A head 48 is threaded into the forward end of the chamber 35 having an instrument receiving kerf 49 therein, while the head 50 which is provided with the stuffing box 38 at the opposite end of the chamber 35 is arranged with spanner wrench receiving 45 sockets 51 for screwing the head 50. A perforation 52 is arranged through the side arm 53 of the base 19 opposite the arm 22 for convenience in attaching the base to a 50 support such as the bracket 18.

The operating mechanism 16 is in the nature of a controller or double valve and provides a substantially cubical block form of casing 54 with a mounting plate 55 for securing the controller to the dash board 15.

An inverted cone-shaped recess or valve chamber 56 extends through the casing 54 with its larger end opening in the top 57 of the said casing and adapted for the reception 60 of a tapered plug 58 arranged for turning in said recess when the controller is assembled, a threaded reduced stem 59 being arranged upon the bottom of the plug for receiving a lock member 60 for maintaining 65 the plug 58 seated within the recess 56.

A passage or port 61 extends through the side of the casing 54 adapted to be connected by means of a suitable pipe 62 arranged through the dash board 15 with the intake manifold 63 of the internal combustion engine, not shown, of the automobile 10. The plug 59 has an annular groove 64 communicating with the inner end of the port 61 when the controller is assembled while an angular port 65 passes through the plug 58 with one end communicating with the groove 64 and its opposite end portion arranged axially of the plug 58, terminating centrally within a tapered bore 66 arranged through a transversely positioned extension 67 upon the top of the said plug 58.

Spaced ports 68 and 69 are positioned in the same transverse plane through the rear side of the casing 54 above the plane and at opposite sides of the suction port 64, pipes 70 and 71 being respectively attached thereto and passing through the dash board 15. The pipes 70, 71 are respectively attached to the pipes 47, 46 of the base chamber 35. A lateral port 72 is provided in the plug 58 communicating with the exhaust port 65 and adapted to be brought into registry with either of the ports 68 or 69 upon turning the plug 58 within the recess 56 and whereby as will be evident, the suction from the motor intake 63 will be communicated to either of the pipes 47 or 46, for operating the piston 36 in the required direction for turning the lamp 20 upon its pivot screw 21 in the desired direction. Longitudinal grooves 73 and 74 are arranged in the side of the plug 58, opening at the top thereof and equally spaced from opposite sides of the transverse port 72.

With the plug 58 arranged within the seat 105 56 of the valve casing 54, a partial revolution of the said plug toward the right will bring the port 72 into communication with the port 69 and at which times the groove 74 will communicate with the port 68. In this manner, the groove 74 through the agency 110 of the port 68, pipes 70 and 47 communicate with the base chamber 35 rearwardly of the piston 36 admitting air at atmospheric pressure rearwardly of the piston 36. At such 115 times also, the chamber 35 is connected adjacent its forward end with the intake manifold 63 for exhausting the air forwardly of the piston 36 by means of the pipe 62, port 61, groove 64, port 65, port 72, port 69, and 120 pipes 71 and 46.

Without further comment it will be seen that the slight turning of the plug 58 of the controller 16 turns the lamp 20 in a direction corresponding to the direction of movement of the said plug. The connections between the intake 63 and piston chamber 35 have been traced when the plug 58 is shifted toward the right, while a shifting of the same toward the left brings the groove 73 into 125 130

communication with the port 69 for admitting atmospheric pressure forwardly of the piston 36 and connects the port 72 with the port 68 for creating a suction back of the 5 piston 36 and turning the lamp 20 toward the left. The lamp 20 is thereby readily turned either toward the right or the left by correspondingly revolving the plug 58 of the controller 16 by the driver positioned 10 upon the seat 12.

A port 75 extends through the rear side of the casing 54 above the vacuum port 61 and is arranged with a pipe 76 passing through the dash board 15 connected to the 15 pipe 34 of the cylinder 26. An annular groove 77 is provided in the plug 58 above the groove 64 and has an angular port 78 passing through the said plug terminating within the bore 66 at one side of the open 20 end of the port 65, it being understood that the groove 77 is always in communication with the port 75 when the device is assembled. It will be seen that by connecting the ports 65 and 78 together in the manner hereinafter 25 described, the manifold 63 will be in communication with the pipe 34 for tilting the lamp 20 upwardly.

A port 79 is provided through the rear wall of the casing 54 beneath the vacuum 30 port 61 having a pipe 80 extending through the dash board 15 and attached to the pipe 33 of the cylinder 26. A groove 81 is arranged around the plug 58 beneath the 35 groove 64 and in constant communication with the port 79, while a port 82 extends through the plug 58 in communication with the groove 81 and with its upper end opening within the bore 66 at the opposite side of the port 65 from the port 78. It will be 40 seen that by effecting communication between the vacuum port 65 and the port 82 that a suction will take place during the operation of the device beneath the piston 28, thereby tilting the lamp 20 downwardly.

An auxiliary plug or valve turn member 45 83 is arranged within the bore 66 preferably having a locking device 84 upon its reduced threaded end 85 while an operating handle 86 radially projects from a head 87 50 upon the opposite end thereof. A longitudinal side groove 88 is arranged in the auxiliary plug 83 adapted for spanning the adjacent upper end of the ports 65 and 78 within the bore 66 when the auxiliary plug 55 83 is slightly rotated from its normal position by moving the handle 86 upwardly. This positioning of the auxiliary plug 83 places a transverse port 89 of the plug 83 in 60 communication with the port 82, thereby exhausting the lower end of the piston chamber of the cylinder 26 to the atmosphere through the cut-away top portion 90 of the main plug extension 67. This upward movement of the handle 86 effects a communication 65 between the manifold 63 and the upper

end of the chamber of the cylinder 26 whereby the lamp 20 is tilted upwardly.

A longitudinal side groove 91 is arranged in the auxiliary plug 83 which is adapted to span and connect the upper ends of the 70 ports 65 and 82, when the handle 86 is moved downwardly. This operation, as will be apparent, effects a communication between the manifold 63 and the pipe 33 at a point beneath the piston 28 for lowering the piston 75 and tilting the lamp 20 downwardly. At such times, a transverse port 92 of the auxiliary plug 83 is positioned in communication with the port 78 for admitting air through the cut-away portion 90 to the pipe 80 34 above the piston 28 and the pressure of which air lowers the said piston when the air therebeneath has been rarefied by the communication of the lower end of the cylinder 26 with the intake 63. It will be seen 85 that the adjacent ends of the port 89 and 92 are always open to the atmosphere through the cut-away portion 90 of the plug extension 67 and that the opposite end of the port 89 is in line with the groove 88 while the 90 corresponding end of the port 92 is in line with the groove 91.

The driver of the automobile 10 may readily tilt the lamp 20 either upwardly or downwardly for throwing its rays at the 95 desired elevation by correspondingly moving the handle 86 of the controller 16 either upwardly or downwardly. The lamp 20 may be swung laterally either toward the right or toward the left by a turning of the 100 plug 58 in a corresponding right hand or left hand direction by the operator grasping the said handle 86. It will also be obvious that the movements of the plugs 58 and 83 by means of the handle 86 are independent of each other and the same may be simultaneously shifted for moving the lamp 20 either toward the right or the left and upwardly or downwardly. The amount of movement of the lamp 20 is accurately 105 controlled by shifting the handle 86 for effecting the desired movement and when the proper position is reached, the plug or plugs are returned to their neutral positions, leaving either of the pistons 28 or 36 at 110 115 any desired intermediate point in the travel thereof.

It will be understood that any lamp such as a spotlight may be shifted at any distance from the controller 16 while any form of suction or exhaust device other than an explosive motor may be employed for operating the device. It will also be seen that the entire mechanism is adaptable for pneumatic control, the operations in such use 120 being substantially opposite to that herein described. While the form of the invention herein set forth is believed to be the preferable embodiment of the device, it will be understood that minor changes may be made 125 130

therein without departing from the spirit and scope of the invention as claimed.

What I claim as new is:—

1. In combination, a shiftable and tilttable member, a double air pressure controlling valve operatively associated therewith whereby the oscillating and tilting movements of the said member may be selectively or simultaneously accomplished.
2. In combination, a tilttable and shifttable member, separate air controlled operating pistons for the tilting and rotary movements thereof, a controlling valve positioned at a distance therefrom, separate air conduits leading from the said valve to the opposite sides of each of said pistons adapted for reciprocating the pistons in either direction and manually controlling means for the valve.
3. In combination, a tilttable and shifttable member, separate air controlled operating pistons for the tilting and rotary movements thereof, a controlling valve positioned at a distance therefrom, separate air conduits leading from the said valve to the opposite sides of each of said pistons adapted for reciprocating the pistons in either direction, air pressure changing means operatively connected to the said valve and manually shifttable controlling means for the valve whereby the first named member may

be selectively or simultaneously tilted or revolved at will.

4. In combination with a tiltably and rotatably mounted lamp, air controlled operating means for the movements of said lamp, a controlling valve therefor positioned at a distance from the lamp and an actuating handle for the valve adapted for imparting tilting and rotary movement to the lamp in a predetermined direction upon tiltingly or rotarilly shifting the said handle.

5. In combination with a base having a piston therein, a lamp rotarilly mounted upon said base adapted for actuation by the piston, an auxiliary piston adapted for tilting the said lamp, a valve casing positioned at a distance from the lamp, air conduits between the said casing and at points adjacent the opposite sides of each of said pistons, an air pressure changing means connected to the said casing, a valve plug rotatably arranged in the casing adapted upon movement for controlling the air connections with the base carried piston for moving the lamp rotarilly and an auxiliary turn plug in the said valve plug adapted upon turning for controlling the said auxiliary piston for tiltably moving the lamp in either direction.

In testimony whereof I affix my signature. 60

JAMES A. SILSSEE.
